INVENTOR.

I. Richard Hibbard.

BY

R. S. Berry,
ATTORNEY.

UNITED STATES PATENT OFFICE.

LOUIS RICHARD HIBBARD, OF LOS ANGELES, CALIFORNIA, ASSIGNOR TO JAMES B. CLOVER, OF LOS ANGELES, CALIFORNIA.

FAUCET.

1,295,500.

Specification of Letters Patent. Patented Feb. 25, 1919.

Application filed July 2, 1917. Serial No. 178,184.

To all whom it may concern:

Be it known that I, LOUIS RICHARD HIBBARD, a citizen of the United States, residing at Los Angeles, in the county of Los Angeles and State of California, have invented a new and useful Faucet, of which the following is a specification.

This invention relates to a faucet and particularly pertains to a faucet embodying an electric liquid heating element.

It is the object of this invention to provide a faucet having a liquid controlling valve, an electric heating element, and a circuit making device adapted on disposing the valve in certain positions to direct currents through the heating element, and by means of which cold, warm or hot water may be delivered from the faucet by turning the controlling valve in various positions.

A further object is to provide a construction and arrangement whereby cold water is directed to the heating coil immediately preceding the completion of the electric circuit through the coil and immediately following the breaking of said circuit, so as to insure the coil being completely submerged while the electric current is passing therethrough, thus protecting the coil against burning out.

Another object is to provide a water heating faucet in which the water discharged therefrom may be heated to various degrees of temperature starting from that of the cold water delivered from the service system and gradually increasing to the boiling point.

Another object is to provide a faucet of the above character which may be readily substituted for the ordinary faucet now generally in use on lavatories, sinks and the like and in which the parts are so formed and assembled that they may be readily removed and replaced when repairs are necessary.

Other objects will appear hereinafter.

The invention is illustrated in the accompanying drawings, in which:

Figure 1 is a perspective view showing the exterior of the faucet.

Fig. 2 is a view in longitudinal section and elevation of the faucet illustrating the course of travel of water therethrough.

Fig. 3 is a view in cross section as seen on the line 3—3 of Fig. 2, a portion of the heating coil being removed.

Fig. 4 is a diagram showing the manner

in which the valve is partly opened to permit water to pass therethrough immediately before completing the electric circuit and immediately after breaking the circuit.

Fig. 5 is a view in section and elevation as seen on the line 5—5 of Fig. 2 showing the switch construction.

More specifically 6 indicates a disk like wall which forms the faucet with a central partition and is externally threaded at each end to receive internally threaded end caps 7 and 8, the end walls of which caps are spaced from the end faces of the wall 6 to form a water compartment 9 and an air compartment 10 on opposite sides of the wall.

The wall 6 is formed with an axial tapered bore in which a rotary valve 11 is mounted, the valve having a stem 12 which projects across the compartment 10 and through the end cap 8 and has a handle 13 affixed to its outer end. A packing gland 14 threaded on a boss formed on the wall encompasses the end of the valve 11 to hold the latter in its seat to prevent leakage into the chamber 10. As a means for draining the chamber 10 in event leaks should occur, a drain aperture 15 is formed in the lower wall of the cap 8. A radial duct 16 is formed in the wall 6 leading from its outer face to the valve; the outer end of the duct being internally threaded to connect with a supply pipe 17.

The valve is formed with a longitudinal passage 18 which opens at one end to the chamber 9. A pair of ports 19 and 20 are formed in the valve wall and spaced apart peripherally thereof and so positioned as to be moved in and out of register with the inner end of the duct 16. The ports are spaced in peculiar relation to each other and to a circuit make and break device as will be later described.

A discharge passage 21 is formed in the wall 6 radially thereof and preferably arranged in alignment with the duct 16 and which passage is internally threaded on its outer end to receive a nozzle 21'.

The passage 21 communicates with the chamber 9 through an opening 22 which passes through a boss 23 forming a seat for a packing ring or gasket 24.

Mounted within the chamber 9 is an insulating member preferably formed of porce-

laid and comprising an annular wall 25 arranged to extend adjacent the end face of the wall 6 and to encircle the inner end of the valve, and which wall carries concentric flanges 26 and 27 on its inner and outer margins. The outer edges of the flanges 26 and 27 are designed to abut against a packing sheet 28 mounted on the inner face of the end wall of the cap 7. An annular channel 29 is thus formed between the flanges 26 and 27 and this channel communicates with the space encircled by the flange 26, into which liquid controlled by the valve is discharged, through an orifice 30 formed in the flange 26. The orifice 30 is disposed in the lower portion of the flange so as to lie below the discharge opening of the valve. The chamber 29 communicates with the discharge passage 21 through an opening 31 registering with the opening 22. The openings 31 and 22 are preferably of a diameter less than that of the intake duct 16 so as to restrict the flow of liquid at this point. The gasket 24 is interposed between the walls 6 and 25 around the openings 22 and 31 so as to prevent the flow of liquid from the valve from passing behind the wall 25 and out the opening 22. This necessitates the passage of the fluid through the annular chamber 29.

Arranged within the chamber 29 is an arculate heating coil 32 the terminals of which connect with binding posts 33 and 34 carried by the wall 6 and extending through an opening 35 in the insulator wall 25. The binding posts 33 and 34 are preferably arranged to extend below and on opposite sides of the orifice 30 and pass through and are insulated from the wall 6.

40 The binding post 33 is formed with a threaded end projecting into the chamber 10 on which is screwed a nut 36 engaging a conductor 37 leading to one terminal of a generator 38. The binding post 34 is also 45 formed with a threaded end to receive a nut 39 engaging an S-shaped spring contact member 40.

A third binding post 41 is arranged in the chamber 10 and engages a second S-shaped 50 spring contact member 42 spaced from the contact 40. A conductor 43 leading from the other terminal of the generator 38 connects with the post 41. The conductors 37 and 43 may pass through the drain opening 55 15 as shown in Fig. 5.

It will now be seen that by connecting the contact members 40 and 42 a circuit will be completed through the heating coil 32.

As a means of completing this circuit I 60 have here shown a pair of blade wiper contacts 44 mounted on the valve stem 12 and insulated therefrom and so arranged thereon that when the valve stem is turned these contact members will engage and electrically 65 connect the contacts 40 and 42 at a proper

time in relation to the opening and closing of the valve ports as will presently be described.

The outer end face of the cap 8 is provided with indicia designating the position of the valve for delivering cold, warm or hot water and for denoting when the valve is closed. The valve stem is fitted with a pointer, in this case the handle 13 serving the purpose, which is so arranged in relation to the ports in the valve as to indicate the position of the valve ports and the switch when pointing toward the various indicia.

Normally, the handle points downward, 8 as shown in Fig. 1, toward the indicia "Off" and when so positioned the valve will be closed and the circuit through the heating element broken.

In the operation of the invention when 8 it is desired to deliver cold water the handle is turned upward either to the right or left to the indicia "Cold" which will position the handle horizontally and move the valve a one-fourth turn. If the handle and 91 valve is turned upward to the right the port 19 will move into register with the inlet duct 16 so that cold water will pass through the valve and out the nozzle at a maximum pressure. If the handle and valve are 95 turned upward to the left the port 20 will be about half open to the duct 16 when the handle is disposed horizontally. When the valve ports and handle are positioned as just described the switch contact member 44 10 will be disposed so as not to connect the contacts 40 and 42.

When it is desired to deliver warm water the valve is turned to the left to dispose the handle above the indicia "Cold", for 10 example, pointing toward the indicia "Warm". The contact member 44 will then be positioned as indicated by the dotted line a in Fig. 4 so as to connect contacts 40 and 42 and direct current through the coil 32. 11 The port 20 will then be wide open so as to deliver cold water to the heating coil at a maximum volume. The heating capacity of the coil is such that when the maximum amount of liquid is passing through the 111 faucet the liquid in rapidly flowing around the coil will be slightly heated.

When it is desired to increase the temperature of the liquid, movement of the valve is continued to the left to partly close port 120 20 and diminish the volume of liquid flowing around the coil. When the handle points toward the indicia "Hot" the parts will be positioned as shown in full lines in Fig. 4 with the port 20 sufficiently closed so 125 that the liquid will pass slowly around the coil and thus be heated to its maximum temperature.

To shut off the hot liquid it is necessary to either retract the handle or continue its 130

movement to the right, past the "Cold" indicia to the "Off" position. In either event the ports 19 or 20 will remain open immediately after the contact member 44 moves out of engagement with the contacts 40 or 42 when cutting off the current through the coil so that cold liquid will flow through the faucet around the coil immediately after cutting the current to the latter. The partly open position of port 20 when the contact member 44 is out of connection with the contact members 40 and 42 is indicated by the dotted line *b* in Fig. 4.

In turning the valve far enough to completely cut off the flow of liquid through the faucet, disconnection of the electric circuit through the coil is insured, as the contact member 44 breaks the circuit when the flow of liquid through the faucet ceases. This, after flow of cold liquid ceases, also insures the coil being submerged at all times and also cooled, thus protecting it against being burned out which might occur if the coil were exposed to the air. The openings 31 and 22 are arranged at the top of the coil and the discharge nozzle leads from the upper portion of the casing so as to insure against drainage of the compartment housing the coil, and to prevent the formation of an air space above the coil to insure the latter being completely submerged, the openings 31 and 22 are arranged close to the flange 27 with the upper part of the opening above the uppermost portion of the coil. By arranging the binding posts 33 and 34 below and on opposite sides of the orifice 30 the liquid passing through the orifice must necessarily flow upward throughout the length of the coil to pass out the discharge opening, thus thoroughly distributing the liquid around the coil so as to be acted on by the entire heating length of the latter.

While I have here shown and described a specific embodiment of my invention, it is

manifest that various changes may be made in the details of the construction without departing from the spirit and scope of the invention as set forth in the appended claims.

50

I claim:

1. In a faucet, a casing, a partition wall forming with said casing a liquid chamber, a radial liquid intake duct in said partition leading from the exterior of the casing, a 55 rotary valve having an open ended passage therein leading to the liquid chamber centrally thereof, ports in said valve adapted to form a communication between the duct and passage, an arcuate electric heating coil 60 in the liquid chamber arranged with its arched portion uppermost and encircling the open end of the valve, a discharge nozzle communicating with the liquid chamber at a point above the uppermost portion of the 65 coil, and means for directing liquid delivered to the liquid chamber downwardly thence upwardly along the heating coil to the discharge nozzle.

2. In a faucet, a casing, a partition wall 70 forming with said casing a liquid chamber, a radial liquid intake duct in said partition leading from the exterior of the casing, a rotary valve having an open ended passage 75 therein leading to the liquid chamber, centrally thereof, ports in said valve adapted to form a communication between the duct and passage, an arcuate electric heating coil in the liquid chamber arranged with its arched portion uppermost and encircling the 80 open end of the valve, a discharge nozzle communicating with the liquid chamber at a point above the uppermost portion of the coil, and an insulator formed with an annular channel in which the coil is disposed, 85 said channel formed with an aperture in the under portion of its inner wall and having an opening communicating with the discharge nozzle.

L. RICHARD HIBBARD.
